UNITED STATES PATENT OFFICE.

ELZA S. STOTTS, OF DES MOINES, IOWA, ASSIGNOR TO THE RAILWAY SIGNAL & EQUIPMENT COMPANY, OF DES MOINES, IOWA, A CORPORATION OF MAINE.

ADJUSTABLE WHEEL-ANCHOR.

1,396,076.

Specification of Letters Patent.

Patented Nov. 8, 1921.

Application filed March 10, 1921. Serial No. 451,297.

To all whom it may concern:

Be it known that I, ELZA S. STOTTS, a citizen of the United States of America, and resident of Des Moines, Polk county, Iowa, 5 have invented a new and useful Adjustable Wheel-Anchor, of which the following is a specification.

The object of this invention is to provide an improved construction for a wheel anchor 10 adapted to be used to anchor a wheel to a railway track when raising the bearings of a car from the journal.

A further object of this invention is to provide a wheel anchor having a vertically 15 adjustable holding head so that a single device may be used under all circumstances, whether or not the wheel rests directly above a tie.

A further object of this invention is to 20 provide improved means for locking the holding head in adjusted position.

With these and other objects in view, my invention consists in the construction, arrangement and combination of elements 25 hereinafter set forth, pointed out in my claims and illustrated by the accompanying drawing, in which—

Figure 1 is a side elevation illustrating the device in position for practical use, a track 30 rail and car wheel thereon being shown in dotted lines. Fig. 2 is a plan, partly in section on the line 2—2 of Fig. 1. Fig. 3 is a detail of the cam locking devices detached and on an enlarged scale.

In the construction of the device as shown 35 the numeral 10 designates a horizontal base member formed at one end with an upwardly extending integral arm 11; and strengthening flanges 12 preferably connect side margins of said arms to the base. The base 10 preferably is formed with a 40 transverse hand hole 13 at its opposite end, by means of which the device may be conveniently carried. The arm 11 is formed with ratchet teeth 13 on its forward or outer 45 face, arranged transversely and preferably extending in series from the bottom to the top of said arm. A holding head 15 is separately formed and is provided on its rear or inner face with ratchet teeth 16 adapted 50 to coat and contact with the teeth 14, so that the holding head may be vertically adjusted on the arm 11. The holding head 15 is formed with an outwardly extending 55 lip or hook 17 at its upper end adapted to

engage the flange of a car wheel such as 18 resting on a track rail 19. To lock the holding head 15 securely in adjusted position on the arm 11 I have shown eccentric latching devices. The arm 11 and straight 60 portion of the head are formed with longitudinal slots 20, 21 respectively, adapted to be wholly or part in register when the parts are assembled. A stem 22 is passed through the slots 20, 21 and is formed at one end 65 with a head 23 contacting the forward face of the holding head 15. The holding head 15 preferably is channeled or grooved on its outer face, adjacent the slot 21, to provide a seat for the head 23 of the stem, so 70 that said head does not project beyond the plane of the outer margin of said holding head. Fixed to the opposite end of the stem 22, by means of a pin 24, is a cam disk 25, slightly spaced from the rear face of the 75 arm 11 and having its face nearest to said arm formed with a succession of alternate depressions and extensions, thus producing a multiple cam surface of undulating form. Loosely mounted on the stem 22 between the 80 cam disk 25 and arm 11 is a coacting cam disk 26 having a smooth forward face in plane contact with the rear face of said arm 11 and an outer face corresponding and adapted to fit snugly against the cam face 85 of the said disk 25. The disk 26 is adapted for rotary movement on the stem 22 and is formed with an integral, laterally extending handle or lever 27, preferably terminating in a ball 28 adapted to be grasped manually. 90 The handle or lever 27 is bent, curved or offset rearwardly between its ends so that the ball 28 is spaced rearwardly from the plane of the arm 11 a considerable distance, and free movement of the handle is permitted.

In practical use the device is employed in a common and well known manner to anchor a car wheel to the rail while raising the bearings from the journal. For this operation 100 the lip 17 is placed in engagement with the rim of the car wheel as indicated in Fig. 1, while a lifting jack (not shown) is placed on the base 10 and employed to raise the journal box and devices connected therewith. 105 The holding head 15 is vertically adjustable on the arm 11 so that the one device may be used under all ordinary circumstances. For instance, if the car wheel happens to stop directly over a cross-tie, the base 10 may be 110

placed on the tie and the device be employed with the holding head raised to elevated position to hold the wheel on the track. In 5 the event the wheel stops between two ties, it is necessary to provide a support for the base 10, bridging the space between the ties, in which case it is necessary to shorten the height of the holding arm a distance approximately equal to the height of the support so employed. In this case the holding 10 head is loosened relative to the arm 11 by turning the handle 27 through an arc to rotate the cam disk 26 to such extent that its cam extensions fit within the corresponding depressions of the cam disk 25. This 15 position permits sufficient longitudinal movement of the stem 22 to allow the teeth 16 of the holding head 15 to clear the teeth 14 of the arm 11, so that the holding head may be 20 adjusted relative to said arm. When the desired adjustment has been made the handle 27 is turned in the opposite direction to cause the extensions of the movable disk 26 to ride on the extensions of the rigid disk 25, thus 25 applying pulling strain on the stem 22 and forcing the holding head 15 toward and in binding contact with the arm 11. The wedging 30 action of the interengaging cam faces may be enhanced by pounding downwardly with the hand or a tool on the outer end of lever 27, which preferably is in substantially horizontal position, as shown in Figs. 1 and 2, when the cam devices are in locked 35 position.

35 I claim as my invention—

1. An adjustable wheel anchor, comprising a base, an arm formed thereon, a holding head adapted to be mounted on and adjustable vertically of said arm, said head being 40 formed with means for engaging a car wheel, said head and arm being formed with overlapping openings, a headed stem extended through said openings and having its head contacting one face of said holding head, a 45 head on the opposite end of said stem spaced from said arm, and a cam disk loosely mounted on said stem between said arm and the last named head, said cam disk having a smooth face in contact with said arm and a 50 wedge face adapted to contact with the last named head, together with a lever formed

on said cam disk and adapted for use in manually turning the same.

2. An adjustable wheel anchor, comprising a base, an arm formed thereon, a holding head adapted to be mounted on and adjusted vertically of said arm, said head being formed with means for engaging a car wheel, said head and arm being formed with registering openings, said head and arm also being 55 formed with serrated contacting faces, a stem passing through the registering openings and provided at one end with means for engaging the outer face of said holding head, said stem being formed at its other end with 60 a head spaced from said arm, and wedging means pivotally mounted on said stem between said head and arm.

3. An adjustable wheel anchor, comprising a base, an arm formed thereon, a holding 70 head adapted to be mounted on and adjusted vertically of said arm, said head being formed with means for engaging a car wheel, said head and arm being formed with registering openings, a stem passing through said 75 registering openings and provided at one end with means for engaging the outer face of said holding head, said stem being formed at its opposite end with a head spaced from said arm, a member pivoted on said stem between said head and arm, said member and head being formed with coacting wedge faces, and means for manually turning said member.

4. An adjustable wheel anchor, comprising 85 a base, an arm formed thereon, a holding head adapted to be mounted in contact with and adjustable vertically relative to said arm, said arm and holding head being formed with 90 serrated contacting faces and with registering slots, a stem passing through said registering slots, and formed with a head at one end countersunk in a groove in said holding head, a head on the other end of said stem spaced from said arm, and wedging means 95 on said stem between said arm and the last named head.

Signed at Des Moines, in the county of Polk and State of Iowa, this 22d day of January, 1921.

ELZA S. STOTTS.
